Patented Mar. 24, 1959

184,670

TRUCK LOAD LIFT UNIT

Leslie G. Ehmann, Portland, Oreg., assignor, by mesne assignments, to Hyster Company, a corporation of Nevada

Application July 25, 1955, Serial No. 37,114

Term of patent 14 years

(Cl. D14—3)

FIG. 1

FIG. 2

FIG. 3

Fig. 1 is a front perspective view of a truck load lift unit showing my new design;

Fig. 2 is a left perspective view; and

Fig. 3 is a front perspective view thereof with the load carriage in elevated position.

The lift truck disclosed in dotted lines is only shown for purposes of illustration.

I claim:

The ornamental design for a truck load lift unit, as shown and described.
